UNITED STATES PATENT OFFICE.

CLARK R. SHELTON, OF NEW HAVEN, CONNECTICUT.

SIGHT FOR FIRE-ARMS.

SPECIFICATION forming part of Letters Patent No. 223,251, dated January 6, 1880.

Application filed November 4, 1879.

To all whom it may concern:

Be it known that I, CLARK R. SHELTON, of the city and county of New Haven, State of Connecticut, have made certain Improvements 5 in Sights for Fire-Arms; and I do hereby declare that the following is a full, clear, and exact description and specification of the same, reference being had to the annexed drawings, making part thereof.

10 My invention relates to what is called the "rear" sight of a fire-arm, and is intended to be placed on the breech of a double-barreled gun, in one of the barrels of which an auxiliary rifle-barrel is to be used; and my invention 15 consists in certain combinations of mechanism, which combinations are specifically set forth in the claim at the end of this schedule.

In order that persons skilled in the art may understand, make, and use my improvements, 20 I will proceed to describe the manner in which I have embodied them, referring to the drawings, in which—

Figure 1 is a rear view of the sight complete as it appears from the breech of the gun, 25 looking toward the muzzle, when attached ready for use. Fig. 2 is a side view, and Fig. 3 is a front view, of the same. Fig. 4 is a top view of the saddle B, which is to be attached to the wood of the breech of the gun. Fig. 5 is 30 a top view of the sight-plate C. Figs. 6 and 7 are front and side views of the standard o.

B is a saddle, which is to be attached to the stock of a shot-gun having two barrels, and for the purpose of such attachment it is provided with screw-holes a b. Its upper surface is provided with two projecting flanges, K K, with a binding-screw, m, arranged in one of them, to hold the slide n, with the upright o and screw-post p, in any position of adjustment required, whether entered from the right hand or the left, to locate the sight for use with the right or left barrel of the arm.

The slide n is provided with an upright standard, o, to which is hinged, at the top, a 45 screw-post, p. On this screw-post is the sight-plate C, having a nut provided with a binding-screw to hold it in any position of adjustment desired, the nut being turned on the screw to raise or lower the sight on the screw.

A spring, s, is attached to the back of o to hold the post firmly in place in a vertical or in the horizontal position shown by the dotted lines of Fig. 1.

The sight is provided with the small peep-hole t and the notches v v', of the usual construction.

The sight and the nut may be turned upside down, if desired, to adapt it to the right-hand or left-hand barrel of the arm.

The use of the sight will be obvious to sportsmen. When the shot-gun is used with an auxiliary rifle-barrel introduced into either shot-barrel, it becomes important to obtain a much more accurate sight than when the shot-barrels are used alone, for in the latter case one 65 central forward sight between the muzzles of the barrels and one central rear sight between the butts of the barrels will be sufficiently accurate; but in using the auxiliary rifle a sight located accurately on the muzzle, over the 70 axis of the shot-barrel containing the rifle-barrel, is required, and also a central rear sight in a plane passing vertically through said axis.

My improvement makes provision for such 75 a rear sight, arranged to be raised and lowered and changed for use with either shot-barrel, and also constructed so that it can be turned down out of the way when not needed, as shown in dotted lines, Fig. 1.

Having now fully described my invention, 80 what I claim, and desire to secure by Letters Patent, is—

The combination, substantially as hereinbefore set forth, of the saddle and the rectangular sight-supporter, arranged to enter and slide toward and from either side of the saddle, its threaded rod, which carries the adjustable sight-plate, being hinged to turn down parallel with the sliding base or at right angles to the gun-stock, all constructed and arranged to operate in the manner substantially as described.

CLARK R. SHELTON.
